INVENTOR

J. C. Mills

BY
E. W. Anderson
his ATTORNEY.

UNITED STATES PATENT OFFICE.

JEFFERSON C. MILLS, OF ANDERSON, INDIANA, ASSIGNOR OF ONE-HALF TO
EZEKIAL A. EGGMAN, OF SAME PLACE.

JAR-CLOSURE.

SPECIFICATION forming part of Letters Patent No. 662,241, dated November 20, 1900.

Application filed September 23, 1899. Serial No. 731,432. (No model.)

To all whom it may concern:-

Be it known that I, JEFFERSON C. MILLS, a citizen of the United States, and a resident of Anderson, in the county of Madison and State of Indiana, have invented certain new and useful Improvements in Jar-Closures; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a perspective view showing the invention as in application. Fig. 2 is a central vertical section thereof. Fig. 3 is a front view of the cover with the gasket removed and the knob provided with a notch. Fig. 4 is a perspective view of the cover and bail, the knob being shown as provided with an aperture.

This invention is designed to provide an improved jar-closure; and it consists in the novel construction and combination of parts, all as hereinafter described, and pointed out in the appended claim.

In the accompanying drawings, the letter A designates the body of the jar, and B the neck portion thereof, the latter having the surrounding groove a, which forms an undercut flange or shoulder b below and surrounding the mouth of the jar. The top edge C of the jar is made perfectly flat to provide a seat for a packing-ring or gasket D of the usual character.

E designates the lid or cover for the jar, formed on its under side with the cylindrical boss e, which is designed to fit within the mouth of the jar. Said boss has a flat bottom surface and is formed with the annular groove f for the purpose of catching and holding the ring or gasket D, the adjacent under surface of the marginal portion of the cover being flat to provide a seat for the upper face of the said ring. The upper face of the lid or cover is somewhat conical in form, with a central knob or handle G and with oppositely-disposed cam rises or inclines H, having notches h in their inclined faces. The knob

or handle G is formed with a lateral notch or recess g, as shown in Fig. 1, or with a transverse aperture g', as shown in Fig. 4, the purpose of such recess or aperture being to provide a seat or bearing for the central portion of a bail-clamp K. Said bail-clamp consists of a piece of wire or metal bent to conform approximately to the contour of the upper surface of the lid or cover, with inturned ends k to engage under the flange or shoulder b. Its shape should be such that when its ends k are engaged with this flange or shoulder and its central portion is engaged with the recess or aperture of the knob and its intermediate portions bearing upon the cam rises or inclines and seated in the notches thereof it will be sprung somewhat from its normally upwardly arched or bowed form or put under tension, so as to press the lid or cover closely to its seat. This spring or tension is due to the fact that the normally arched bail is forced down at its central and highest portion into engagement with the notch in the knob. The peripheral edge of the flange or shoulder b is also preferably formed with notches, as at b', to hold the clamp from slipping by the locking engagement therewith of the lateral upwardly-extending arms of said clamp.

The clamp can be very quickly applied in closing the jar or removed in unclosing the same, while the manner in which it is seated and secured prevents any liability of its slipping and becoming loose. The knob G in addition to its function in providing a bearing for the clamp also serves as a convenient handle.

Having thus described my invention, what I claim as new, and desire to secure by Letters Patent, is—

The combination with the jar having an inwardly-offset annular shoulder, and annular corrugations or teeth at its upper portion, of a cover having opposite lateral toothed inclines, and a central knob provided with an opening therethrough; and a bail-clamp having an upwardly arched or bowed transverse arm engaging the opening of said knob and the teeth of said inclines, being thus depressed

at its central portion under the action of said inclines to more securely engage the same, and lateral depending arms in locking engagement with the annular corrugations or 5 teeth of said jar, and having inturned ends in engagement with said annular groove of the jar, substantially as specified.

In testimony whereof I affix my signature in presence of two witnesses.

JEFFERSON C. MILLS.
